Primary Examiner — Brandon M Rosati*Assistant Examiner* — John A Voytek(74) *Attorney, Agent, or Firm* — Foley & Lardner LLP(57) **CLAIM**

I claim the ornamental design for a walk in bath, as shown and described.

DESCRIPTION

FIG. 1 is a perspective view of the claimed design;
FIG. 2 is a front view of the design shown in FIG. 1;
FIG. 3 is a top view of the design shown in FIG. 1;
FIG. 4 is a cross-sectional view of the design shown in FIG. 1 taken along line 4-4 in FIG. 3;

FIG. 5 is another cross-sectional view of the design shown in FIG. 1 taken along line 5-5 in FIG. 3;
FIG. 6 is another cross-sectional view of the design shown in FIG. 1 taken along line 6-6 in FIG. 3; and,
FIG. 7 is yet another cross-sectional view of the design shown in FIG. 1 taken along line 7-7 in FIG. 3.

The ornamental design which is claimed is shown in solid lines in the drawings. The broken lines in the drawings depict only environmental subject matter and form no part of the claimed design. The dash-dot lines indicate boundaries between claimed and unclaimed portions of the design.
